AUTOMATIC ALARM SYSTEM

Hans Teodor Nicou, Stockholm, Sweden

Application January 13, 1938, Serial No. 184,892
In Sweden January 20, 1937

4 Claims. (Cl. 177—311)

This invention refers to automatic alarm systems having one or more control circuits, sections or loops connected to a source of current, such as a battery, and normally closed, each section being provided with means, such as circuit-breakers, for breaking the circuit in case of fire or other danger. These circuit-breakers are arranged in the localities to be watched over through which said section or sections are drawn.

The chief object of this invention is to create an automatic alarm system which may be built and operated at low costs but nevertheless is safe in operation and very reliable.

Another object of this invention is to simplify the construction of electric alarm systems, without reducing their reliability and safety of operation. In particular, the raising of alarm shall be secured also under unfavourable conditions.

Another object of this invention is to render it possible to increase the number of circuit-breakers, thermo-contacts or fuses to be used in each section, while still retaining a high selectivity and rendering it easy to localize a fault or a fire.

Another object of this invention is to render it possible to localize the position of a fault or a danger, such as a fire, more accurately and more rapidly than heretofore.

Another object of this invention is to give an automatic and reliable indication of the position of a fault or a danger, by simple and inexpensive means.

Another object of this invention is to reduce the length of the wires necessary for the control circuits or sections, without reducing the reliability and the safety. Thus, the system will be less expensive and also less exposed to line faults and fault signals.

Other objects will be evident from the following specification and claims.

Embodiments of the invention are illustrated in the annexed drawings.

Fig. 1 shows an electric alarm system in accordance with this invention.

Fig. 2 shows a modification.

Referring now to Fig. 1 of the drawings, I and II indicate two control circuits, sections or loops drawn through the localities to be watched over. It is understood that the number of sections is arbitrary, though only two sections are shown for the sake of clearness. In some cases one single section may be used. Each section comprises two conductors or wires *a*, *b* and a number of circuit-breakers, thermo-contacts or fuses *T*, it 55

being understood that multiple-wires sections may also be used. The parts below the dash-and-dot-line C—C are arranged in a central post.

The branch or wire *b* of section I has one end 5 connected with the + pole of a central battery *B* via the winding of a section relay *R_b* and the normally closed contact *b_v* of that relay which is normally energized like all the section relays. The other end of that wire is connected with an 10 inner point of the battery *B* at the tap 10 via the normally closed contact *b_h* of the relay *R_b*. To that same tap 10 one end of the wire *a* of section I is connected via the winding of section relay *R_a* and the normally closed contact *a_h* of that relay. The opposite end of the same wire *a* 15 is connected with the — pole of the battery *B* via the normally closed contact *a_v* of the relay *R_a* and the small protective resistance *m*.

The wires of section II and the other sections, 20 if any, are connected to the battery taps in quite similar manner. The section relays of section II are indicated by *R_{IIb}* and *R_{IIa}*.

The contacts *a_v*, *a_h*, *b_v*, *b_h* are double, the upper contact of each pair being normally closed while 25 the lower one is normally open.

Two milliamperemeters *A_v*, *A_h* are provided, each connected in series with a battery *B₁* and *B₂*. These amperemeters are connected with the normally open contacts of the pairs *a_v*, *a_h*, *b_v*, *b_h*. 30 The right-hand ammeter *A_h* is connected with one such contact at *b_h* and another at *a_h* of the relays *R_a*, *R_b* of section I and also with the same contacts of the relays *R_{IIa}*, *R_{IIb}* of section II etc. Similarly, the left-hand ammeter *A_v* is connected 35 with the normally open contacts *a_v*, *b_v* of the sections. Taps for connecting further sections to the ammeters are shown at 8.

In the embodiment as shown in Fig. 1 the milliamperemeters *A_v*, *A_h* are common to all sections, while each section has its individual section relays *R_a*, *R_b*, *R_{IIa}*, *R_{IIb}*.

Two preferred embodiments of thermocontacts or fuses are shown in detail and on a larger scale in section I.

45 In the left-hand thermocontact *T* of section I the contact springs 3, 4 are soldered together by means of a low-melting soldering metal in such manner that these springs will spring apart when the solder melts as a result of a temperature 50 higher than that permissible in the locality to be controlled in which the thermocontact is placed. By these means a reliable breaking of the contacts 3, 4 is secured, when the solder fuses. When the springs 3, 4 thus spring outwards they make contact with contact pieces or wires 5, 6

so that a contact between the wires *a*, *b* is brought about on both sides of the break. The melting of a thermocontact *T* consequently results in a breaking of both wires *a*, *b* and a contact between wires *a*, *b* of different signs on both sides of the break. Because the pieces 5, 6 both have the same function, there is double safety for really effecting a contact between the wires *a*, *b*.

The right-hand thermocontact *T* of section I differs from the thermocontact just described substantially in this that one single contact piece or cross-conductor *T* is arranged on each side of the contact springs 3, 4. The conductor *T* may consist of a simple metallic cross-piece secured to a pillar or plinth, around which the base plate of the thermocontact is cast or pressed.

The section relays *R_a*, *R_b*, *R_{IIa}*, *R_{IIb}* also have normally closed contacts *k_v*, *k_h*. The contacts *k_h* of relays *R_a*, *R_{IIa}* and those of the section relays of wires *a* of additional sections, if any, are connected in series in a circuit from the + pole of battery *B₁* through of contacts *k_h*, conductor 100, winding of normally energized alarm relay *AR_a* back to the - pole of *B₁*. A similar circuit extends from the - pole of battery *B₁* through all the contacts *k_v* in series, conductor 101, winding of normally energized relay *AR_b* to the + pole of *B₁*.

A normally open alarm circuit extends from + pole of battery *B* via normally open contacts of relay *AR_b*, conductor 103, fire alarm *BS*, conductor 102, contacts of relay *AR_a* back to - pole of *B*. The circuit is not closed until both alarm relays *AR_a*, *AR_b* fall off simultaneously and close their contacts.

When an alarm relay *AR_a*, *AR_b* is de-energized and falls off, its contacts also close an obvious circuit for a signal lamp *AL_a*, *AL_b*, respectively.

In addition to the devices shown, there may be provided the ordinary switches, signal lamps, signal bells, code wheels etc., as well-known in the art; see for instance United States Patent No. 2,059,510. They form no part of this invention and are, for this reason, not shown. The arrangement of the alarm relays and the fire alarm as shown herein is also shown in said patent and forms no part of the present invention.

Reference is made to the fact that the arrangement of the sections I, II and their connection with taps of the battery *B* is substantially shown and claimed in a United States Patent application (Serial Number 184,100) by Olof Ingemar Harald Ekman and Hans Teodor Nicou. However, the sections may be arranged in any well-known or suitable manner, for instance, as shown in United States Patent No. 2,059,510.

As described in said patent and patent specification, and as is evident from the annexed drawings and the foregoing description, when a wire, say wire *a* of section I, is broken the corresponding section relay *R_a* is de-energized and released, breaking its contact *k_h*. Thus the circuit for alarm relay *AR_a* is opened at *k_h* and that relay is released and closes its contacts. This closes the circuit for lamp *AL_a* which is illuminated and indicates the fault. But the circuit for the fire alarm *BS* remains open at the contacts of relay *AR_b*. Similarly, if a wire *b* is broken, its section relay, say *R_b*, is de-energized and releases *AR_b*. If both a wire *a* and a wire *b* are broken simultaneously, both relays *AR_a*, *AR_b* are released and close the circuit for the fire alarm *BS* so that alarm is raised.

When both relays of a section, say *R_a*, *R_b* of

section I, are thus de-energized in case of fire, the upper normally closed contacts of the pairs *a_v*, *a_h*, *b_v*, *b_h* are opened and the lower, normally open ones are closed so that the milliamperemeters *A_v*, *A_h* are connected with the wires *a*, *b* of the section I broken. Then the circuits for the ammeters are as follows:

(1) From + pole of battery *B₂*, through lower contact at *b_h*, right-hand part of wire *b* to the thermocontact broken (indicated by a broken line), across to the wire *b*, back through right-hand part of wire *b*, lower contact at *a_h*, ammeter *A_h* to - pole of *B₂*.

(2) From + pole of battery *B₁*, through lower contact at *b_v*, left-hand part of wire *b* to the thermocontact broken, across to wire *a*, back through left-hand part of wire *a*, lower contact at *a_v*, ammeter *A_v* to - pole of *B₁*.

Thus, the two ammeters are automatically connected with that section, say I, which has been broken and now measure the intensities of the currents through the wires of different signs (*a*, *b*) connected together, on both sides of the thermocontact broken. It is evident that these ammeters, if properly graduated, directly indicate the position of the break, for instance, by means of a code number or other mark. There are two circuits (1) and (2) above for indicating the break, giving double security. If, as a result of bad contacts at the springs 3, 4 of the thermocontact fused, the two ammeters show different indications, the ammeter giving the highest indication or deviation should be followed.

Because a break of a section giving a high deviation of one ammeter gives a low deviation of the other, the ammeters should, preferably, be graduated in opposite directions. By suitable reversion they may, of course, be graduated in the same direction. The needles of the ammeters may also be arranged co-axially on the same dial so that the needles register both normally and after a section has been broken. In case of difference, it is then easier to see which needle has the greatest deviation. It is to be observed that a greater difference between the deviations of the ammeters indicates that several thermocontacts are broken. Consequently, the ammeters indicate the limits of the spread of the fire.

In the plant shown the relays *R_a*, *R_b*, *R_{IIa}*, *R_{IIb}* in the normal manner indicate the sections in which a fault has occurred or from which alarm is given. In accordance with this invention the sections may be made far greater than heretofore, without any inconveniences, because the milliamperemeters which are automatically cut in in case of alarm, directly localize and indicate that thermocontact which has been broken. For instance, the number of thermocontacts of a section may be increased to 100 or more. This is very advantageous. Because it is necessary to draw wires back to the central post say for each group of 100 thermocontacts only, the total length of wire required is reduced, while simultaneously the indication is far more precise than in the systems heretofore known. The reduced length of wire—for the same total number of thermocontacts—means lower costs of construction and lower risks of faults. Simultaneously the system has the highest degree of reliability, because alarm is certainly raised when two wires *a*, *b* are broken, and the raising of alarm is independent of the local indication effected by the ammeters.

Referring now to Fig. 2 of the drawings, condensers 9 are inserted between the wires *a*, *b*, one condenser being provided at each thermocontact. The condenser may be placed on either side of the thermocontact. Preferably, the condenser is inserted into a recess of the base plate of the thermocontact, is soldered to the terminals of the thermocontact and coated with a suitable solidifying mass, protecting the condenser against moisture etc.

In this embodiment, a source of alternating or pulsatory current is provided in the central post for the milliamperemeters. In Fig. 2 said source is illustrated as current-breaking buzzers *S* sending a pulsating current through the milliamperemeters *A_v*, *A_h*, when the relays of a section, say *R_a*, *R_b*, are released simultaneously. But for the buzzers with their batteries an inductor or a relay device or a mechanically driven switch which alternately charges and discharges a central condenser battery, may be substituted.

In the embodiment shown in Fig. 2 ordinary thermocontacts or fuses are used which only are broken in case of fire but do not interconnect the wires *a*, *b* on both sides of the break. In other respects the plant shown in Fig. 2 is similar to that shown in Fig. 1 and corresponding parts carry the same reference characters. Also the operation is quite similar.

When a thermocontact is broken in the system shown in Fig. 2, the amperemeters and their sources *B₁*, *S*; *B₂*, *S* of alternating or pulsating current are automatically connected with the section, say *I*, containing that thermocontact. As described in connection with Fig. 1, the left-hand amperemeter *A_v* is connected with those parts of the wires *a*, *b* which are to the left of the broken contact *T* (indicated by a broken line) while the right-hand amperemeter *A_h* is connected with those parts of the same wires which are to the right of the broken contact. For each unbroken thermocontact in these left and right parts a condenser 9 is inserted between the wires *a*, *b* and lets through a partial or shunt current between them. If the condensers 9 are of approximately the same size and the ohmic resistance of the wires may be neglected, this being quite permissible if the wires are properly dimensioned, the amperemeters directly indicate the position of the broken thermocontact, because the intensity of the current is substantially proportional to the number of condensers in the left or right parts, respectively, and consequently to the number of thermocontacts between the measuring instrument *A_v*, *A_h* and the break.

Also in this embodiment the giving of alarm is quite independent of the condensers 9 and the instruments *A_v*, *A_h*. A break or a short-circuit in a condenser does neither put the system out of operation nor prevent alarm from being raised properly. A break in a condenser only has the effect that in case of alarm the thermocontact next to that actually broken is indicated as broken, that is: the break only causes an indication incorrect by a single step. A short-circuit within a condenser 9 is immediately indicated by one of the section relays as an ordinary short-circuit or leakage between the wires, for instance, as described in U. S. Patent No. 2,059,510 or the U. S. patent application Serial No. 184,100 referred to above.

In the plants shown in Figs. 1 and 2, it is possible to have an indication in accordance with the present invention, say for every second

or every fifth thermocontact *T*. In such case, only every second or fifth thermocontact has a condenser 9 or cross-contact-making means 5, 6, 7, while the remaining thermocontacts are of the ordinary design without any condensers or cross-contacts.

In the plant shown in Fig. 2 the condensers may have graded sizes depending upon their distance from the central post, to compensate for the ohmic resistance of the wires *a*, *b*.

In the embodiment shown, the amperemeters are automatically connected with wires *a*, *b* in case of alarm. Obviously, this may be made manually by use of switches or keys, instead of automatically. All thermocontacts of a whole plant may be included in one single section, indication by means of milliamperemeters being provided say for every twentieth or thirtieth thermocontact. Such system has a very low cost of construction and is in many cases sufficient. As a rule, however, it is preferred to distribute the thermocontacts on several sections, say 100 thermocontacts per section. Each section need not have its own section relays in the central post; on the contrary the sections may be connected in series, only two section relays being provided which are common to all sections. In the central post a suitable kellog-switch or the like is provided for each section. When a fault occurs in a section, and is indicated, that section is disconnected from the other by use of said switches and is connected with a special alarm relay common to all sections, while the remaining sections are still connected in series.

In this case suitable resistances of different sizes are inserted into the sections at their both ends connected with the central post, rendering it possible to differentiate the sections and their thermocontacts more easily by means of the amperemeters.

If the sections connected in series are constructed in accordance with Fig. 2, the amperemeters will first indicate the section in which a break occurs. After that section has been disconnected from the others and is alone connected with the amperemeters, the latter will indicate the position of the broken thermocontact within the section.

It is to be observed that the plants as shown above do not include any movable selectors or similar mechanical devices, this being favourable for a high reliability. However, selectors or finders may be used for connecting the amperemeters to the alarm-giving section.

This invention may also be applied to plants having one or more single wire sections, the earth serving as a return path for the current. For operating the milliamperemeters parts of the central battery *B* may be used instead of the batteries *B₁*, *B₂*. Only one milliamperemeter may be used but two milliamperemeters give a double control and also an indication of the extension of the fire.

Reference is made to the fact that the plant shown in Fig. 2 has no additional contacts to be closed in the thermocontacts in case of fire. For this reason the reliability is as high as possible.

It may be mentioned that this invention may very advantageously be applied to ships and other structures comprising a great number of small localities to be controlled. In such case the high localizing capacity of this system is of special importance, because the systems heretofore known cannot effect such localizing of high ex-

actitude, by means of devices economically possible.

If two sections simultaneously release alarm, which is improbable, the watchman, seeing the lamps of two sections burning simultaneously, has to connect the milliamperemeters manually with those sections one after the other to establish where the break is in each of those sections. But, of course, automatic means, such as relays, may also be used for connecting the milliamperemeters with only one section at a time.

What I claim is:

1. In an automatic electric alarm system, in combination, a loop of insulated wires normally closed extending through the locality to be watched over, current-breakers in said wires responsive to the cause of danger to be warned against, condensers connected at intervals between said wires, a source of current connected to said wires to deliver current to them, as long as they are unbroken, said current being of a character to which said condensers set a high resistance, a second source of current of sufficiently high frequency that said condensers set a comparatively low resistance to the flow of it, means for electrically measuring the current from said second source, when connected to one end of said loop, after one of said current-breakers is opened, and an electric alarm mechanism connected to said wires to raise alarm, when one of said current-breakers is opened.

2. In an automatic electric alarm system, in combination, a battery for direct current, a loop of insulated wires normally causing direct supervisory current and connected to said battery and extending through the locality to be watched over, current-breakers in said wires responsive to the cause of danger to be warned against, condensers connected in parallel between said wires at intervals between said current-breakers, a source of pulsatory current for cooperating with one end of said loop, said pulsatory current having sufficiently high frequency that even one of said condensers sets a comparatively low resistance to said pulsatory current, means for measuring said pulsatory current passing through one or more of said condensers, when one of said current-breakers has been opened, and an electric alarm mechanism connected to said wires to raise alarm, when one of said current-breakers is opened.

3. In an automatic electric alarm system, in combination, a loop of insulated wires normally closed and extending through the locality to be watched over, current-breakers in said wires responsive to the cause of danger to be warned against, condensers connected at intervals between said wires, a source of current connected to said wires to pass current normally through said wires, as long as they are unbroken, the current delivered by said source being of such a character that it is substantially incapable of passing through said condensers, two sources of pulsatory current each for cooperating with one end of said loop, said pulsatory current being capable of passing through even one of said condensers with a low resistance, current-measuring means each connected with one of said two sources of pulsatory current for measuring the pulsatory currents through one or more of said condensers from both ends of said loop, when one of said current-breakers has been opened, and electric alarm mechanism connected to said wires to raise alarm when one of said current-breakers is opened.
4. In an automatic electric alarm system, in combination, a loop of insulated wires normally closed and extending through the locality to be watched over, current-breakers in said wires responsive to the cause of danger to be warned against, condensers connected in parallel at intervals between said wires, a source of current connected to said wires to pass current normally through said wires as long as they are unbroken, the current delivered by said source being of such a character that it is substantially incapable of passing through said condensers, normally closed section relays in said wires, an alarm apparatus connected with said relays to raise alarm, when one of said current-breakers is opened and releases said relays, a second source pulsatory current connected with said relays to be connected with one end of said loop when said relays are released, the current delivered by said second source of current being of sufficiently high frequency that it is capable of passing easily through one or more of said condensers, and means associated with said second source of current for measuring the pulsatory current when said relays are released.

50 HANS TEODOR NICOU.
